Fig. 4.

This technical drawing illustrates a mechanical assembly, likely a component of a larger machine. The drawing is a cross-sectional view showing the internal structure and external components. Key labeled parts include:

- D**: A vertical plate or frame on the left side.
- G**: A large rectangular housing or base structure.
- C**: A horizontal slot or opening in the base structure.
- K**: A horizontal rod or beam spanning the width of the base structure.
- X**: Two points on the horizontal rod, likely indicating supports or attachment points.
- B**: A vertical component located on the left side, connected to the base structure.
- H**: A vertical component located on the top left, connected to the base structure.
- M**: A vertical component located on the top left, connected to the base structure.
- F**: A vertical component located on the right side, connected to the base structure.
- J**: A vertical component located on the left side, connected to the base structure.
- I**: A vertical component located on the left side, connected to the base structure.
- Y**: A vertical component located on the right side, connected to the base structure.

The drawing uses a coordinate system with a vertical axis labeled 'Y' and a horizontal axis labeled 'X' at the top center. The base structure is supported by four vertical legs, one on each corner. The internal mechanism includes various rods, bearings, and a central horizontal beam.

UNITED STATES PATENT OFFICE.

JESSE D. COTTRELL, OF HOPEDALE, MASSACHUSETTS.

IMPROVEMENT IN LOOMS.

Specification forming part of Letters Patent No. **149,448**, dated April 7, 1874; application filed March 28, 1874.

CASE A.

To all whom it may concern:

Be it known that I, JESSE D. COTTRELL, of Hopedale, in the county of Worcester and State of Massachusetts, have invented certain new and useful Improvements in Looms; and I do hereby declare the following to be a full, clear, and exact description of the same, reference being had to the accompanying drawing forming part of this specification, in which—

Figure 1 is a side elevation. Fig. 2 is a partial rear elevation. Fig. 3 is a section through line *x x*, Fig. 4; and Fig. 4 is a front elevation.

Similar letters of reference in the accompanying drawings indicate the same parts.

My invention relates to improvements in the let-off and take-up mechanism of looms, by means of which, in the absence or breakage of a weft-thread, said mechanism ceases to operate, and is an improvement on the patent granted to me, dated May 4, 1869, No. 89,561.

In the accompanying drawings, *A A* are the uprights or standards of the loom, in which are journaled the cloth-beam *B* and yarn-beam *C*, in the ordinary manner. *D* is the lay, hung on the rod *E*, pivoted to the cross-beams *F F*, connecting the standards or uprights *A A*. *G* is the breast-beam, on the upper face of which are securely attached the stands *H H*, provided with slots *I I*, extending through them, in which operate the arms *J J*, attached to the rod *K*, journaled in the standards *A A*, or in brackets attached to the upper part of the loom-frame. *L L* are projections attached to the upper face of the stands *H H*, at the ends of the slots *I I*, and fit into the slotted plates *M M*, placed over the stands *H H*. Pivoted in the plates *M M* are the levers *N N*, to the upper faces of which are attached the springs *O O*, adjustable by means of slots and screws, or screws to engage with the upper extremities of the arms *J J*. *P P* are short slots in the plates *M M*, in which the short arms of the levers oscillate. *Q Q* are short levers journaled in the front ends of the slots *P P*, the outer ends being recessed and lying under the short arms of the levers *N N*. To the rear ends of each arm *Q* is attached a vertical finger, *R*, which, together, form the feeling-fork. In recesses in

the race *S* are securely attached plates *T T*, right-angularly formed, the vertical part of which is composed of rods *S' S'*. *U* is a shaft journaled in the cross-bars of the loom, and provided with cranks *V V*, connected by arms *W W* to the lay, and by means of which a reciprocating movement is given the latter. *X*, Fig. 4, is a shipper-rod, journaled in the front standards of the loom, and provided at its ends with right-angled arms *Y Y*. *Z* is a bent arm attached to the rod *K*, the inner end of which projects over one of the cross-bars connecting the standards of the loom. To one end of the rod *K* is attached the crank-arm *a*, the outer end of the horizontal arm of the crank being provided with a truck or roller, *b*, which operates in a slot, *c*, in the pitman *d*, the inner end of which is eccentrically attached to the crank-shaft *U*. The outer end of the pitman is governed in its movements by the crank *a*, and its roller working in the slot *c* of the pitman, and the crank is operated by the arms *J J*, attached to the rod *K* through the levers *N N*. *e* is a lever journaled on a stud, *f*, attached to one of the standards, the upper end of said lever being bent at right angles, the bent portion of the arm lying over the outer end of the pitman. *g* is a hook or pawl attached to the lever *e* above its fulcrum, and engages with a ratchet-wheel, *g'*, on the end of the cloth-beam.

From this construction and arrangement of parts, it will be seen that when the lay moves forward and the weft-thread is unbroken, it will be carried forward by the grids on the race, and, striking the feeling-forks *R R*, will depress the rear ends *Q Q*, and engage the long arms of the levers *N N* with the arms *J J* on the rod *K*, and the take-up and let-off mechanism are operative. In case of the absence of a weft-thread to operate the levers *N N*, the arms *J J* will pass under the long arm of the levers *N N*, being brought into that position by the weight of the crank or bent arm *Z*, attached to the rod *K*, in which case the forward end of the pitman is brought in contact with the crank or arm *Y Y* of the shipper-rod, and the cloth-beam ceases to revolve and stops the loom.

To the lower end of the lever *e* is attached

the rod g^2 , which passes through a right-angled bracket, h , attached to one of the cross-pieces of the frame. The opposite end of the rod e is attached to the lower end of a brake-arm, h' , pivoted to a stud on the frame of the loom. The upper end of the brake is curved, as seen at i , to embrace a friction-roller, j , journaled on a stud, k , attached to the frame of the loom. l is a pinion on the stud k , which meshes into a gear-wheel, m , on a shaft, n , journaled in the standard, the shaft U passing through the standard, and is provided on its inner end with a pinion, o , which engages with a gear-wheel, p , on the yarn-beam. q is a spring surrounding the connecting-rod g^2 , one end of which spring bears against the bracket h , the other end of the spring bearing against a collar, r , adjustable on the rod g^2 . s is a brake, pivoted to a stud, t , on a bracket, u , attached to one of the loom-standards, the outer end of said brake bearing against the under surface of the friction-roller j . v is an adjustable rod passing through an eye or hole in the lower end of the bracket u . The upper end of the rod v lies under and against the brake s when the lay beats up. In all other positions of the lay the brake s rests upon the spring w , which surrounds the adjustable rod v . The lower end of the spring w bears against an adjustable collar, x , on the rod v . y is the warp-guide, of the ordinary construction, to one end of which is journaled the arm z , to the outer end of which is pivoted the rod a' , the lower end of which bears against the upper face of the brake s , the rod also passing through an eye in the bracket u . b' is a spring surrounding the rod a' , the lower end of which bears against a projection on the bracket u , the upper end of said spring bearing against an adjustable collar, c' .

The function of the spring q is to cause the curved brake s to hold the friction-roller j securely at all times, except when the take-up mechanism operates. The adjustable collar r on the rod g^2 is used to vary the tension of the springs q .

When the take-up mechanism operates and the curved brake $i h'$ is released from contact with the friction-roller j , the tension of the yarn on the warp-guide y depresses the arm z and rod a' , and removes the brake s from contact with the friction-roller j , and allows the let-off mechanism to operate.

Having thus described my invention, what I claim is—

1. The stands H H, constructed as set forth, in combination with the slotted plates M M, levers N O, fork Q R, and arms J J, attached to the rock-shaft K, substantially as described, and for the purpose set forth.

2. The rock-shaft K, provided with the crank a , carrying a truck or roller, b , in combination with the slotted pitman d and shipper-rod X, having an arm, Y, substantially as described, and for the purpose set forth.

3. The take-up mechanism, consisting of the pitman d and pawl-lever e , in combination with the connecting-rod g^2 , surrounded by a spring, q , curved brake $i h'$, and friction-roller j , substantially as described, and for the purpose set forth.

4. The brake s and friction-roller j , in combination with the rods $a' v$, surrounded by springs, adjustable collars $x c'$, and warp-guide y , substantially as described, and for the purposes set forth.

JESSE D. COTTRELL.
